ROTARY ABRADING STRIP HOLDER

Lawrence Lynch, Los Angeles, Calif.

Application June 2, 1952, Serial No. 291,119

3 Claims. (Cl. 51—194)

1

This invention relates to abrading and buffing rollers such as used for polishing the tools in which plastic articles are molded. Such polishing is generally a very delicate operation which requires expert handling of a perfectly balanced buffing tool.

It is in view of the foregoing the object of my invention to provide a simple and inexpensive tool which is so perfectly balanced that it can be depended upon for the most delicate polishing operations at the very high speed of rotation of such tools. Another object of the invention is to provide a device in the form of a roller whereon a flexible strip of abrasive material may be mounted and which includes means for drawing the strip of material tightly and evenly about the roller. These and other objects of the invention as well as the many advantageous features thereof will be better understood upon perusal of the following detailed description and by referring to the accompanying drawing in which preferred forms of the invention are illustrated.

In the drawing:

Fig. 1 is an end view of a buffing roller embodying the invention;

Fig. 2 is a substantially corresponding side elevational view of the device;

Figs. 3 and 4 illustrate the element of the invention by means of which a strip of abrasive material may be tightly supported on the roller, substantially in the manner indicated in Fig. 1; and

Figs. 5, 6 and 7 illustrate a modified form of the invention.

The roller shown in Figs. 1 and 2 comprises a cylindrical core 1 to the peripheral surface of which a soft resilient lining 2 is rigidly secured. The roller is shown mounted on a spindle 3 for insertion into the jaws of the machine ordinarily employed to rotate the roll at high speed.

A passage 4 extends axially through the case of the roller and a slot 5 is cut into the surface of the roller leading into this passage of a size to admit the ends of a strip A of an abrasive material into the passage. The inner surface of the passage is threaded to receive therein a threaded strip tightening element 10. A transverse slot 11 is cut into this element from one end thereof and of a depth and width to receive therein the ends of the abrading strip A and a thin disc 12 is seated in the open end of the element rigidly to maintain the shape of the element undisturbed during the operation of the device.

It is important to note that an arcuate recess 6 is cut into the inner surface of the passage 4

2

adjacent the slot 5 and of a width to receive therein the layers of the abrading strip when the element 10 is operated to secure the strip in position on the roller. In order to perform this operation, it is merely required to advance the element into the passage 4 until the slot 11 is in axial alignment with the slot 5 of the roller. The strip of abrasive material is then folded about the roller end the ends of the strip pushed through the slot of the roller into the slot of the element until the strip fits snugly about the roller. When thereupon the element is rotated in the direction of the arrow of Fig. 2, it is found that the layers of the strip will be forced into the recess 6 tightly to clamp the strip in position on the roller. It was above stated that the polishing to be performed is a delicate operation requiring a very light perfectly balanced tool. The core 1 of the roller is for this reason made from very light, soft material, such as aluminum. But because the tightening element is of tenuous construction and is subjected to considerable strain in clamping the lining in position on the core, it becomes necessary to employ much stronger material, such as steel or bronze, and since such material is so much heavier, it is found that the weight of the tightening element will urge the roller out of balance when rotated at high speed. Some means must be provided to overcome this difficulty and I have found that cutting holes of the proper diameter axially into or through the core and as close to the tightening element as possible, substantially as indicated at 15 in Fig. 1, perfect balance may be restored.

The modified form of device illustrated in Figs. 5 to 7 differs from the foregoing merely in the manner in which the element 20 is held against axial displacement within the passage 16 of the roller.

The outer cylindrical surface of this element and the inner surface of the passage 16 are both smooth and of a size snugly to seat the element therein. The means for maintaining the element axially in position within the passage includes a pin 21 which is seated in the roller to project into an annular groove 22 of the element. Once the element has been in such manner applied to the roller, it is merely required to rotate the element, in the same manner that the element 10 is rotated, tightly to clamp the strip in position on the roller.

Means should be provided for facilitating rotation of the elements, and such means is in Fig. 1 shown to take the form of a hexagonal recess 14 in the end of the element and of a size to re-

ceive therein a suitable key. If preferred, a slot 23 may be cut in the end of the element, as indicated in Fig. 7 for receiving an ordinary screw driver.

I claim:

1. A support for a strip of material comprising, a roller having a threaded cylindrical passage axially therethrough near the outer surface thereof, the portion of the roller between the passage and the surface of the roller being cut to provide a slot leading into the axial center of the passage and of a width to admit therethrough the ends of the strip to be supported, a threaded cylindrical strip tightening element extending through and fitted to rotate in the threads of said passage, the element having a slot axially sunk into one end thereof for alinement with the roller slot to receive therein the ends of the strip fed through the roller slot, there being an arcuate recess in the threaded wall of the passage adjacent one edge of the roller slot of a depth to receive therein the layers of the strip when the element is rotated to force the layers of the strip into said recess, and a thin spacing disc rigidly seated in the slot of the element at the outer end thereof.

2. A support for a strip of material comprising, a very light roller having a cylindrical passage axially therethrough near the outer surface thereof, the portion of the roller between the passage and the surface of the roller being cut to provide a slot leading into the axial center of the passage and of a width to admit therethrough the ends of the strip to be supported, and a cylindrical strip tightening element extending through and fitted to rotate within said passage, said element being made from much heavier and stronger material, the element having a slot axially sunk into one end thereof for alinement with the roller slot to receive therein the ends of the strip fed through the roller slot, there being an arcuate recess in the wall of the passage adjacent one edge of the roller slot of a depth to receive therein the layers of the strip when the element is rotated to force the layers of the strip into said

5

recess, there being passages axially through the roller near the cylindrical passage therethrough of the proper diameter to reduce the weight of the roller about the element sufficiently to balance the roller.

10

3. A support for a strip of material comprising, a very light roller having a cylindrical passage axially therethrough near the outer surface thereof, the portion of the roller between the passage and the surface of the roller being cut to provide a slot leading into the axial center of the passage and of a width to admit therethrough the ends of the strip to be supported, a cylindrical strip tightening element extending through and fitted to rotate within said passage, said element being made from much heavier and stronger material, the element having a slot axially sunk into one end thereof for alinement with the roller slot to receive therein the ends of the strip fed through the roller slot, there being an arcuate recess in the wall of the passage adjacent one edge of the roller slot of a depth to receive therein the layers of the strip when the element is rotated to force the layers of the strip into said recess, there being passages axially through the roller near the cylindrical passage therethrough of the proper diameter to lighten the roller about the element sufficiently to balance the roller, and a spacer rigidly seated in the slot of the element at the open end thereof.
